UNITED STATES PATENT OFFICE.

HENRY M. LOOMER, OF BEVERLY, MASSACHUSETTS, ASSIGNOR TO UNITED SHOE MACHINERY COMPANY, OF PATERSON, NEW JERSEY, A CORPORATION OF NEW JERSEY.

MACHINE FOR OPERATING UPON THE HEELS OF BOOTS AND SHOES.

1,160,989.

Specification of Letters Patent. Patented Nov. 16, 1915.

Application filed July 25, 1911. Serial No. 640,437.

To all whom it may concern:

Be it known that I, HENRY M. LOOMER, a citizen of the United States, residing at Beverly, in the county of Essex and State 5 of Massachusetts, have invented certain Improvements in Machines for Operating Upon the Heels of Boots and Shoes; of which the following description, in connection with the accompanying drawings, is a specification, 10 like reference characters on the drawings indicating like parts in the several figures.

This invention relates to heel breasting machines and is herein shown and described as applied, by way of example, to a machine designed to operate upon heels which are to have a breast face of double curvature, such as are known in the art as "orthopedic" or "anatomic" heels. It has 15 been customary to breast heels of this sort upon the ordinary heel breasting machine by merely substituting a knife having a double curvature for the ordinary straight knife, or knife of single curvature, and substituting for the ordinary presser plate another having an end portion shaped to correspond to the knife of double curvature. It is found in practice, however, that in order 20 properly to locate the longitudinal median line of the heel with respect to the central portion of a knife of double curvature, in treating different heels, it is necessary to move the shoe laterally. Moreover, it is necessary, in order to effect a 25 change of contour of the heel breast, to change the knife to one of different curvature. It is also found that the presser plate could not be accurately adjusted to the contour of the knife in prior machines, because 30 in such machines provision is made for adjusting the presser plate only longitudinally of a heel, which movement alone fails to bring the front end of the plate into correspondence or parallelism with the double 35 curved contour of the knife. It has also been found necessary in prior machines, in order to breast properly shoes of different sizes, to change knives to correspond with the size of shoe being treated,—the knife 40 used on the smaller shoe having a similar shape to that used on the larger shoe but made upon a reduced scale.

It is an object of the invention, therefore, to provide means for adjusting a shoe later-

ally relatively to the knife, so that a change 55 in contour of the heel may be effected without change of knives, and, a further object of the invention is to provide means whereby the foreparts of different shoes may be swung predetermined distances in opposite 60 directions whereby a further change of contour of the heel breast may be effected without change of knives.

It is also an object of the invention to provide means for effecting proper adjustment 65 of the edge of the presser plate into parallelism with the contour of the rear side of the knife.

It is a further object of my invention to provide means whereby heels of widely 70 varying sizes may be given breasts of substantially uniform appearance by the use of the same knife.

An important feature of the invention comprises a work support upon which the 75 shoe is held during the breasting operation which is provided with means for effecting its adjustment transversely of its line of movement for bringing a shoe into and out of position for the breasting operation. The 80 work support is pivoted at its lower end and the means which provides this pivotal movement is mounted for sliding adjustment upon its trunnion, means being provided for clamping the support in any position of 85 lateral adjustment while yet permitting its pivotal movement into and out of operative position. This lateral adjustment enables the heel to be positioned with its median line 90 at various points along the knife edge, so that with a double curved knife considerably wider than the usual heel the median line of the heel may be brought into different positions along the curved knife edge, and hence heel breasts of widely varying configuration may be produced by the use of a 95 single knife.

Another feature of the invention consists in the combination of a work support constructed and arranged to permit a shoe 100 mounted thereon to be swung transversely, with a freely laterally moving member adapted to contact with the shoe to determine its transverse position, means being also provided for predetermined and adjusting the 105 amount of movement of the said member. Means is thus provided for positioning the longitudinal median line of the heel in op-

posite oblique angular relations to the plane of the breasting knife by adjustment of the movement of the member and thus equally and oppositely limiting the movement of the forepart engaging means into these angular relations. This feature is, of course, applicable to breasting rights and lefts with straight or single curved knives and when used with an ogee knife provides for still further varying the contours of the heel breasts without necessitating change of knives, by giving the support for the toe portion of the shoe a predetermined amount of movement equally in either direction to vary the relation of the heel to the knife. The lateral movement of the toe support, together with a slight movement of the heel in the direction of its longitudinal median line, moreover, furnishes means for 20 breasting widely varying sizes of heels so that the appearance of their breasts is practically identical.

Another feature of the invention consists in a work support having a lateral adjustment in combination with a toe rest having a transverse swinging movement whereby a still further increase in the number of variations in contour may be effected by varying the position of the heel relatively to a single 30 knife of double curvature.

Another important feature of the invention comprises a presser plate which preferably is moved downwardly to bring it into contact with the heel of the shoe and clamp the same upon the work support and which is mounted for lateral, as well as longitudinal, adjustment so that all portions of the curve of its front edge may be adjusted to substantially the same distance from the 40 back side of the knife. Since the knife and the front edge of the presser plate have a double or ogee curvature, the usual adjustment provided for the presser plate in a line perpendicular to the plane of a straight knife or to the general plane of a double curved knife is insufficient to bring all portions of the curve of the presser plate into close proximity to all portions of the rear face of the double curved knife. With the 50 lateral adjustment, however, in connection with the longitudinal adjustment, the presser plate may be accurately adjusted with its front edge parallel to the rear face of the double curved knife. Moreover, in the construction shown the same means which holds the plate against movement laterally holds it from movement longitudinally. Hence, by manipulation of a single means, adjustment in both directions may be effected simultaneously.

Another feature of my invention comprises means for holding the presser plate which contacts with the work so that it may be readily detached. Means is provided for preventing longitudinal movement of the

plate relatively to its support but permitting transverse movement, as stated, and means is provided for clamping the plate upwardly against its support when it has been adjusted to the proper lateral position. The 70 support upon which the plate is held may be adjusted longitudinally, thereby effecting a longitudinal movement of the presser plate, and both the transverse and the longitudinal movements of the presser plate may be effected at the same time and both the plate and its support may be held in position by the same clamping means. By further loosening the same clamping means, furthermore, the plate may be removed, reversed 75 and replaced and may then be clamped in position as before. In the reversed position, the plate may be used in connection with a knife having a curvature reverse to that of the knife first used, this change of knives 80 being necessary for breasting right and left orthopedic heels.

These and other features of the invention will appear more fully from the following detailed description in connection with the 90 accompanying drawings, and will be pointed out in the appended claims.

In the drawings:—

Figure 1 is a front elevation of the improved breasting machine; Fig. 2 is a sectional detail, illustrating the mechanism for effecting the lateral adjustment of the shoe support; Fig. 3 is a perspective view, partly in section, of the mechanism for effecting the adjustment of the lateral swinging movement of the toe rest; Fig. 4 is a perspective view of the presser plate and its supporting clamping means, taken from a position below the same; Figs. 5, 6 and 7 are diagrammatic views showing the relation of various 100 heels to the knife.

In Fig. 1 the reference character 2 indicates the frame of a power heel breasting machine of the usual type, power being continuously applied to the pulley wheel 4 from which it is transmitted to the breasting knife through suitable mechanism involving a one-revolution clutch which is arranged to be tripped by the treadle 6. Prior to the action of the treadle in tripping the clutch, however, it acts through the rod 8, the spring 10, the lever 12 and the vertically movable slide 14 to depress the presser plate 76 upon the heel of the shoe to clamp the shoe upon the shoe support in position to be breasted. Upon the tripping of the clutch by further movement of the treadle the knife 50 is actuated to breast the heel, the stop 60 descending with the knife and contacting with the shank of the shoe when the knife has passed through the material of the heel. Upon contact of the stop 60 with the shank of the shoe, mechanism is operated to disconnect the knife from its actuating mechanism, thereby arresting its cutting action 125

and preventing the knife from cutting into the shank. The mechanism thus far described is of the usual type and forms no part of the present invention.

5 The jack post 20 upon which the work is supported is mounted at its lower end, Fig. 2, for swinging movement upon a stub shaft 21. Between the stub shaft 21 and the post 20 is interposed a collar 22 carrying a flange 10 23 which has frictional engagement at 24 with a surface formed on the machine frame. To prevent endwise movement of the collar 22 and its flange 23 relatively to the stub shaft 21, a set screw 25 is threaded into the 15 end of the stub shaft 21 and carries a washer 26 which bears upon the end of the collar 22. At the opposite end the stub shaft carries a resilient friction plate 29 which is fixed from rotation thereon by means of pins and a 20 screw, as indicated in Fig. 2. The friction plate bears against a surface 31 on the machine frame and the collar 22 is thus held from free rotation by the frictional contact between the surface 24 on the machine frame 25 and the flange 23, which contact is maintained by the action of the resilient plate 29 in forcing the stub shaft 21 and collar 22 with its flange 23 toward the right. The post 20 is clamped to the collar 22 by means 30 of a bolt 27 which passes through the post 20 and is provided with a notch overlying the cylindrical surface of the collar 22. The bolt 27 is actuated longitudinally by a hand nut 28, Fig. 1. It will now be seen that when the bolt 27 is freed by loosening the nut 28, the post 20 may be slid longitudinally of the collar 22 to adjust the work support transversely of the machine and to bring the longitudinal median line of the heel of the shoe 40 upon the support to various positions along the edge of the knife 50. When the hand nut 28 is tightened, however, the bolt 27 is moved longitudinally and by reason of the notch therein is clamped against the cylindrical surface of the collar 22, thereby maintaining the post 20 in rigid relation to the collar 22 and preventing transverse movement thereof.

50 A forepart contacting member, shown as a toe rest 30 which is formed to receive and center the forepart of the shoe relatively thereto, is carried upon an arm 31 extending laterally and upwardly from the jack post 32 which carries the heel pin or iron last. 55 To provide means to permit lateral movement of the forepart contacting member, it is mounted upon the supporting arm 31, and means is provided for adjusting the extent of the movements of the arm. The lower end of the arm 31 is provided with a sleeve 33, Fig. 3, which embraces a sleeve 34 having a shoulder 35 upon which the sleeve 33 rests. The sleeve 34 is adjustably secured to the jack post 32 by means of a 60 screw 36 passing through an ear 37 and

threaded into an ear 38. The sleeve 33 is provided at 40 with a V-shaped opening or notch, which embraces a pin 42 carried by a slide 44 which is mounted for vertical adjustment in the sleeve 34. Upon the upper face of the sleeve 33 and freely engaging a reduced portion of the sleeve 34 is an internally threaded collar 46, the threads of which engage the threaded upper portion of the slide 44. Vertical movement of the collar 46 relatively to the sleeves 33 and 34 is prevented by a washer 48 which is secured to the sleeve 34.

It will now be clear that with the pin 42 in the position shown the sleeve 33 and arm 31 may have a certain amount of rotative movement relative to the sleeve 34 in either direction until the pin 42 contacts with the sides of the notch 40 and it will also be apparent that turning of the collar 46 will adjust the pin 42 vertically so that it may be made to contact with different vertical portions of the sides of the V-shaped notch so as to provide greater or less movement of the collar 33 relatively to the collar 34 and hence to permit greater or less swinging movement for the arm 31 carrying the toe rest.

Referring now to Fig. 4, the vertically movable slide 14, which, as described, is operated from the treadle 6, carries upon its lower end a block 61 pivoted to the slide 14 at 62 and normally held in position with its lower face substantially horizontal by a spring 64 connected to a pin 65 on the block 61 and a pin 66 upon the rearwardly extending arm of the slide 14, the line of the pins being normally above the axis 62 of the block 61. The presser plate support 68 is mounted upon the block 61 for longitudinal adjustment, by means of a headed stud on its upper side which engages a T-way in the block shown at 63, Fig. 1, and by a clamping screw 70 by which it is held clamped against the lower face of the block 61. The screw 70 passes through the three-point clamp 72, through a slot 73 in the rear portion of the supporting plate 68, and is threaded into the block 61. The three-point clamp 72, instead of bearing against the support 68 at its forward end, bears against the presser plate 76 which is thereby held clamped against the support. The presser plate 76 rests at its rear edge against pins 78 and has slots intermediate its ends engaging pins 79, the slots permitting a certain amount of lateral movement of the plate 76 relatively to the support 68. It will now be seen that when the clamping screw 70 is loosened by means of the thumb head 71 the support 68 may be moved longitudinally carrying with it the plate 76, that the plate 76 may be adjusted laterally relatively to the support 68 and that both will be held in clamping position by tightening the screw 125 130

70. It will be further apparent that by sufficiently loosening the screw 70 the plate 76 may be moved downwardly to free it from the pins 79 and may then be removed and replaced, the other side up, its curved edge then assuming the position indicated in dotted lines in Fig. 4. The plate will then serve for use with a knife having an opposite curvature to that employed with the 10 plate when in the full line position. The clamping plate may accordingly be adjusted longitudinally and laterally and may be removed, reversed, replaced and again clamped in position by the manipulation of 15 a single clamping screw.

In the use of the machine, a knife having a double curvature is secured in adjusted position in the usual manner by the clamping nuts 51 in the knife carrier 52. The 20 presser plate 76 having a front edge with a curvature corresponding to that of the knife is placed in position upon the pins 78 and 79 and under the clamp 72. It is then adjusted longitudinally and laterally until its edge is 25 in parallelism with the contour of the rear side of the knife, and the clamping screw 70 is tightened to hold the plate in adjusted position. Heels having a breast face of 30 double curvature may now be breasted upon the machine, but will be identical in contour. To effect change of contour, the post 20 may be loosened upon the collar 22 and adjusted laterally to position the shoe with its longitudinal median line in different relation to 35 the curve of the knife and the contour of the breast thereby changed without necessitating a change of knives. This feature is shown diagrammatically in Fig. 5 in which two lateral positions of the heel are represented in dotted lines in relation to the knife 40 shown in section. A further change of contour of the heel breast may be effected by permitting a swinging movement of the toe rest 30 or by varying the extent of that 45 swinging movement by adjusting the pin 42 vertically through manipulation of the collar 46, as described. The effect of swinging the toe upon the relation of the heel breast to the knife is illustrated in Fig. 6 where the 50 outline (in dotted lines) of various heels of widely divergent contour are shown as capable of being breasted upon a single knife by swinging the shoe about a vertical axis.

Fig. 7 indicates diagrammatically how 55 heels of different sizes may be given breasts of similar appearance by swinging the shoe and moving it slightly in the general direction of the longitudinal median line of the heel. In this way the ratio of the length 60 of one side of the heel to the length of the other side is kept the same irrespectively of the size of the heel, and the proper length and width of the portion of the heel projecting under the instep arch is maintained. 65 For this purpose the lateral movement may

be combined with the swinging movement, if desired. After all the shoes of a certain kind, either rights or lefts, have been breasted it is necessary to change the knife to one of similar, but reverse, curvature. The necessity of providing a separate presser plate for the second knife is, however, obviated in the present invention by reversing the presser plate and clamping it in position the other side up.

Having described my invention, what I claim as new and desire to secure by Letters Patent of the United States is:—

1. In a heel breasting machine the combination with a knife having a double curved cutting edge, of means to support and actuate the knife, a shoe support for holding a shoe in proper vertical relation to the knife, and a toe rest mounted for swinging movement to vary the relation of the longitudinal median line of the heel to the knife edge for varying the contour of the heel formed by the cutting action of the knife.

2. A heel breasting machine, having in combination, a knife having a double curvature, means to support and actuate the same, and means to support the shoe against the action of the knife, said means having provision for adjustment in the general direction of the extent of the knife edge to vary the position of the longitudinal median line of the heel to the curvature of the knife whereby various contours of heel are breasted by the knife.

3. In a heel breasting machine the combination with a knife having a double curvature, of means to support and actuate the knife, a presser plate arranged for contact with the tread face of the heel, means for effecting relative movement of the shoe and plate to jack the shoe, and means for effecting adjustment of the presser plate in two directions substantially perpendicularly to the knife.

4. In a heel breasting machine the combination with a knife having a double curvature, of means to support and actuate the same, a presser plate arranged for contact with the tread face of the heel and mounted for adjustment transversely of the median line of the heel, and a shoe support for clamping the shoe against said presser plate, said support being mounted for adjustment in the same direction as the present plate.

5. In a heel breasting machine the combination with a knife having a double curved edge, of means for supporting and actuating the same, a presser plate arranged to engage the tread face of the heel, a shoe support upon which the shoe is clamped by the presser plate comprising a heel support and a toe rest, an arm carrying the toe rest and mounted for movement about a point beneath the heel rest, to vary the relation of the longitudinal median line of the heel to

the curve of the knife, and means for limiting the swing of the toe rest.

6. A heel breasting machine having, in combination, a knife, means for supporting and actuating the knife, a presser plate arranged to engage the tread face of the heel of a shoe, and means for positioning the shoe relatively to the knife for right and left breasting comprising a heel rest, a toe rest to engage the exterior of the forepart of the shoe and between which and the knife there is provision for relative angular movement into positions for such right and left breasting, limiting devices for predetermineding the amount of such angular adjustment, and means for effecting adjustment to change simultaneously for each direction of movement the extent of angular movement allowed for such right and left breasting.

7. In a heel breasting machine the combination of a knife having a double curvature, means for supporting and actuating the same, a shoe support movable into and out of position under the knife in the direction of the longitudinal median line of the heel to properly locate different sized heels relatively to the knife, and means for swinging the heel about a vertical axis whereby heels of various sizes may be given breasts of the same appearance when breasted by the same knife.

8. In a machine for breasting orthopedic heels, a work support mounted for adjustment laterally of the heel, a knife of double curvature, and a presser plate shaped to correspond to the knife and mounted for adjustment laterally of the knife.

9. A heel breasting machine, having, in combination, a double curved knife, means for holding and actuating the same, and a work support mounted for adjustment laterally of the heel to bring the longitudinal median line of the heel into different relations to the knife for varying the double curved contour of the heel breast upon different shoes.

10. In a heel breasting machine, the combination with means to hold and actuate knives of varying curvature, of a presser plate having a front edge contoured to fit one knife when placed one side up and another knife when placed the other side up, and means for supporting and actuating the plate to clamp the shoe.

11. In a heel breasting machine, a presser plate, and means for supporting and actuating the presser plate to clamp a shoe, said presser plate being mounted on the support for lateral adjustment relatively to the shoe.

12. In a heel breasting machine, a presser plate, a support therefor, means to actuate the support to bring the presser plate into

contact with the work, means on said support against which the rear edge of said presser plate abuts, and a clamp for holding the presser plate against the support.

13. In a heel breasting machine, a presser plate, a support therefor, means to actuate the support to bring the presser plate into contact with the work, means on said support against which said presser plate abuts when forced rearwardly, and a clamp having two points of contact with the presser plate and one with the support.

14. In a heel breasting machine, a presser plate, a support therefor, means to actuate the support to bring the presser plate into contact with the work, means for preventing rearward movement of the presser plate, a triangular member arranged to overlie an edge of the presser plate and to rest also on the support, and means for clamping the triangular member against the support and presser plate.

15. In a heel breasting machine, a presser plate carrier, a presser plate support mounted for sliding adjustment longitudinally upon the carrier, a presser plate mounted for lateral adjustment upon the support, and a single clamping means for holding the support and the plate in adjusted position upon the carrier.

16. In a heel breasting machine, a presser plate carrier, a presser plate support mounted for sliding adjustment longitudinally upon the carrier, a presser plate arranged to be held either side up for lateral adjustment upon the support and for removal therefrom by movement in a direction away from the support, and a single clamping means for holding the plate in adjusted position and for permitting, when loosened, lateral adjustment of the plate and removal thereof.

17. In a heel breasting machine, a vertically movable presser plate support, means for actuating the same, a plate provided with slots, pins on the support arranged to engage said slots, abutment pins arranged to engage the rear edge of the plate and means for clamping the plate against its support.

18. In a heel breasting machine, a vertically movable presser plate support, means for actuating the same, a plate arranged for lateral movement in the support, a clamp engaging the plate and the support at separated clamping points, and a clamp screw located between the clamping points for clamping the plate to the support.

19. In a heel breasting machine, a reciprocating knife, means for actuating the same, means for supporting the heel portion of the shoe, means for clamping the heel upon the support, a toe rest for engaging externally the toe portion of the shoe, said rest being

pivoted for lateral movement about a point beneath the heel rest to position the shoe relatively to the knife for right and left breasting, and means for adjustably limiting 5 the lateral swinging movement of the toe rest.

20. In a machine for operating upon the bottoms of boots and shoes, the combination with working means, of a shoe support for 10 sustaining the rear portion of the shoe but permitting the forepart to be swung from side to side, a freely swinging member arranged to engage the forepart of the shoe externally and to move with the shoe relatively to the support of the rear portion as 15 it is swung relatively to the working means to properly position the heels of right and left shoes relatively thereto, and adjustable means for limiting the swinging movement 20 of the forepart engaging means.

21. In a heel breasting machine a breasting knife mounted for reciprocation, a work support constructed and arranged to permit a shoe mounted thereon to be swung about a 25 point located beneath the heel, a member movable about a point beneath the heel and adapted to remain in contact externally with the forepart of the shoe to determine its transverse position in angular relation to 30 the plane of reciprocation of the breasting knife to position the shoe relatively to the knife for breasting rights and lefts, and means for predetermining equal and opposite angular positions of the said member 35 relatively to the plane of the knife.

22. In a heel breasting machine the combination of a knife mounted for vertical reciprocation, a shoe support constructed and arranged for positioning movement beneath 40 the knife, means contacting externally with the fore part of the shoe and pivoted to said support beneath the heel part of the shoe, said means being arranged when swung to position the longitudinal median line of 45 the heel in opposite oblique angular relations to the plane of the breasting knife, and adjustable means for equally and oppositely limiting the movement of the forepart engaging means into said angular relations.

50. 23. A heel breasting machine having, in combination, a knife, means for supporting and actuating the knife, a presser plate arranged to engage the tread face of the heel, a shoe support comprising a jack post carrying a heel rest, an arm extending forwardly from the jack post and outside of the shoe, a toe rest mounted on the arm, said rest being movable to positions on opposite sides of a line normal to the general plane of the 55 knife, and means for limiting movement of the rest to predetermined equal and opposite distances from said normal line to position 60

the shoe relatively to the knife for breasting the heels rights and lefts.

24. A heel breasting machine having, in 65 combination, a knife, means for supporting and actuating the knife, a presser plate arranged to engage the tread face of the heel, and shoe positioning means comprising a jack post carrying a heel support and a forepart rest extending forwardly externally of the shoe to a point beneath the toe portion thereof, said rest being curved to engage and center the shoe relatively thereto and supported for limited movement laterally to position right and left shoes in opposite angular relations to the general plane of the 70 knife.

25. A machine of the class described, having, in combination, a knife, means for actuating the same, and a shoe support comprising a relatively stationary heel supporting portion and a forepart engaging member mounted for lateral movement to position the shoe with the longitudinal median line 80 of the heel at predetermined equal and opposite angles to the plane of the knife.

26. A machine of the class described having, in combination, means for operating upon shoe heels and with relation to which means a left shoe has to be positioned differently from a right shoe, a shoe support, clamping means engaging the shoe heel for holding the heel for the action of the operating means, means for engaging the toe portion of a last covered by the upper and movable with the shoe, and means for limiting the movement of the toe portion engaging means in opposite directions to position right and left shoes respectively for the action of 100 the operating means.

27. A machine of the class described having, in combination, means for operating on shoe heels and with relation to which means a left shoe has to be positioned differently 105 from a right shoe, a shoe support, clamping means engaging the shoe heel for holding the heel upon the support for the action of the operating means, means for engaging the toe portion of the upper covered last, said 110 means being formed to center a shoe relatively thereto and movable with and by the shoe, and means for limiting the movement of the toe portion engaging means in opposite directions to position right and left 115 shoes respectively for the action of the operating means.

In testimony whereof I have signed my name to this specification in the presence of two subscribing witnesses.

HENRY M. LOOMER.

Witnesses:

CHESTER E. ROGERS,
LESTER A. HOWE.

It is hereby certified that in Letters Patent No. 1,160,989, granted November 16, 1915, upon the application of Henry M. Loomer, of Beverly, Massachusetts, for an improvement in "Machines for Operating upon the Heels of Boots and Shoes," an error appears in the printed specification requiring correction as follows: Page 4, line 119, claim 4, for the word "present" read *presser*; and that the said Letters Patent should be read with this correction therein that the same may conform to the record of the case in the Patent Office.

Signed and sealed this 21st day of March, A. D., 1916.
